UNITED STATES PATENT OFFICE

168,005

AUTOMOBILE

Walter Wiggins, Jr., Beaver Heights, Md.

Application July 7, 1952, Serial No. 20,491

Term of patent 14 years

(Cl. D14—3)

To all whom it may concern:

Be it known that I, Walter Wiggins, Jr., a citizen of the United States, residing at Beaver Heights, in the county of Prince Georges and State of Maryland, have invented a new, original, and ornamental Design for an Automobile, of which the following is a specification, reference being had to the accompanying drawing, forming part thereof.

Figure 1 is a side elevational view of an automobile, showing my new design;

Figure 2 is a top plan view thereof;

Figure 3 is a front view; and

Figure 4 is a rear view of the same.

I claim:

The ornamental design for an automobile, as shown.

WALTER WIGGINS, JR.
